UNITED STATES PATENT OFFICE.

JAMES O'BRIEN AND ADOLPH A. LUEKE, OF LOUISVILLE, KENTUCKY, ASSIGNEES, BY
MESNE ASSIGNMENTS, TO ALFRED ISENBERG, OF LOUISVILLE, KENTUCKY.

DOOR.

1,085,470.

Specification of Letters Patent.

Patented Jan. 27, 1914.

Application filed December 13, 1912. Serial No. 736,627.

To all whom it may concern:

Be it known that we, JAMES O'BRIEN and ADOLPH A. LUEKE, citizens of the United States, residing at Louisville, in the county 5 of Jefferson and State of Kentucky, have invented new and useful Improvements in Doors, of which the following is a specification.

This invention relates to improvements in 10 doors such as are commonly employed in elevators, freight cars, buildings, ships and other structures and has particular application to that type of door employing a number of sections slideable one upon the 15 other to open and close the doorway which the door controls.

In carrying out the present invention, it 20 is our purpose to provide a door of the class described wherein in the sliding movement 25 of the first section to open and closed positions, such section will travel at a speed greater than that of the adjacent section so that a uniformity of movement will be brought about between the sections constituting the door when the sections are operated to open and closed positions and wherein the sections may be operated quickly and with ease and facility.

It is also our purpose to provide a locking means through the medium of which the 30 sections of the door may be locked in door closing position, the locking means being constructed in such manner as to operate automatically and lock the door in closed position 35 immediately succeeding the movement of the sections of the door to such position.

Furthermore, we aim to provide a mechanism by means of which the sliding sections 40 of the door may be operated at the relative speeds aforesaid and which will embrace the desired features of simplicity, efficiency, durability and strength coupled with cheapness of cost in manufacture and which may be applied to any type of sectional sliding 45 door in use.

With the above and other objects in view, the invention consists in the construction, combination and arrangement of parts hereinafter set forth in and falling within the 50 scope of the claim.

In the accompanying drawing; Figure 1 is a rear elevation of a sectional door equipped with the present invention. Fig. 2 is a horizontal sectional view on the line

2-2 of Fig. 1, and Fig. 3 is a detail view of 55 the locking mechanism.

Referring now to the accompanying drawing in detail, the numerals 1, 1 designate the door jambs of the frame of the door opening, while 2 indicates the door as an 60 entirely composed, in the present instance, of sections 3, 4 and 5, the sections 3 and 4 being adapted to slide one upon the other and upon the section 5, while the latter is connected by means of hinges 6 to one of 65 the jambs 1 so that, when the occasion arises, the door may be swung to an open position to leave the door opening unobstructed.

In the ordinary use of the door, the section 70 3 is slid upon the section 4 and the latter together with the first section slid upon the section 5 to open the doorway and moved in a reverse direction to close the doorway. In accordance with the present invention, 75 we employ a mechanism whereby the first section may, in the movement of the door to to open and closed positions, slide upon the second or adjacent section at a speed greater than that of the second section in sliding 80 upon the last or stationary section of the door. In the present instance, we employ for this purpose a bar or lever 7 having one extremity fulcrumed or pivoted upon a pin 8 fastened in any suitable manner to the 85 hinged edge of the section 5 of the door, adjacent to the lower end of such edge. The section 4 of the door has connected in any suitable manner at the rear edge thereof at a point approximately centrally of its 90 length a guide 9 designed to receive a pin 10 carried by the bar or lever 7 and extending outwardly of one side thereof, while the rear edge of the section 3 of the door adjacent to the upper end thereof has appropriately connected thereto a guide 11 designed to receive a pin 12 fastened to the free end of the lever or bar 7 and extending outwardly of the side of the bar opposite from the pin 10. By arranging the pins to ex- 100 tend in relatively opposite directions, the lever, when connected with the respective sections of the door, is disposed in an out of the way position and nicely fitted or disposed in operated position.

By connecting 105 the guide 11 to the rear edge of the section 3 or first section of the door adjacent to the top of such section and the guide 9 to the

rear edge of the second or adjacent section at a point approximately centrally of the height of such section, the first section of the door in its movement to open and closed 5 positions travels at a speed approximately twice as great as that of the adjacent or second section of the door, owing to the fact that the radius or distance from the pivot point of the lever to the second section of the door is in direct proportion to the radius from the center of the second section to the top edge of the first section. Thus, when the section 3 of the door is actuated to slide to an open position, such section travels at a speed greater than that of the second section, while when the sections of the door are moved to closed position, the first section travels at a relatively great speed as compared with that of the 10 second section.

In order to lock the sections of the door in closed position and to bring about such locking action automatically, suitable locking means is employed. In this case, a lever 13 is pivoted at a point between its ends upon a pin 14 carried by the guide 11 adjacent to the top edge of the first section of the door. One end of the lever 13 has the upper edge thereof rounded as at 15 and is 15 normally held in the path of movement of the adjacent part of the lever or bar 7 by means of a suitable form of spring 16 carried by the guide, while the opposite end of such lever 13 is equipped with a weight or 20 the like 17 which acts to hold the lever normally in a horizontal position. Thus, when the operator wishes to open the door, that is to slide the sections relatively to one another to clear the doorway, the weighted end of 25 the lever 13 is depressed whereby the locking end thereof is moved out of the path of movement of the bar or lever 7 so that the latter may operate as aforesaid, the spring 16 restoring the locking lever to normal 30 position upon such lever being released by the operator. In the movement of the sections of the door to closed position, the lower edge of the bar or lever 7 engages the 35

rounded edge 15 of the locking lever 13 and so swings the latter about the pivot pin 50 14 so that the bar or lever 7 may assume its proper position. When the rounded end of the locking lever is relieved of the influence of the bar, such lever is restored to locking position by means of the weight 17 55 and prevents accidental sliding of the door sections.

While we have herein shown and described one preferred form of our invention by way of illustration, we wish it to be understood that we do not limit or confine ourselves to the precise details of construction herein described and delineated as modification and variation may be made within the scope of the claim and without departing from the spirit of the invention.

We claim:

The combination with a door comprising a number of sections adapted to slide one upon the other, of a lever movable about a fixed 70 fulcrum, connections between said lever and sliding sections at relatively different points whereby the first section will move at a greater speed than the adjacent section, a locking lever pivoted to said first section 75 adjacent to one end and adapted for swinging movement in a vertical plane and normally resting in a horizontal plane and having the upper corner thereof adjacent to the pivotal connection rounded and disposed 80 in the path of movement of said lever whereby when the sections are extended the lever will be locked automatically, a weight on the free end of said locking lever for returning the same to locking position succeeding the 85 engagement of the first-mentioned lever with the rounded end of the second lever, and a spring for holding said lever normally in locking position.

In testimony whereof we affix our signatures in presence of two witnesses.

JAMES O'BRIEN.
ADOLPH A. LUEKE.
